UNITED STATES PATENT OFFICE.

JULIUS H. SCHLAFLY, OF CANTON, OHIO, ASSIGNOR TO THE BERGER MANUFACTURING COMPANY, OF CANTON, OHIO, A CORPORATION OF OHIO.

BASE FOR COMPOSITION FLOORS.

1,093,653.

Specification of Letters Patent. Patented Apr. 21, 1914.

Application filed February 20, 1912. Serial No. 678,928.

To all whom it may concern:

Be it known that I, JULIUS H. SCHLAFLY, a citizen of the United States, residing at Canton, in the county of Stark and State of Ohio, have invented a certain new and useful improvement in a Base for Composition Floors.

My invention relates to improvements in specially formed metallic plates or bases designed to be used as a support for composition floors, the object being to generally improve such bases and to provide a construction which will be strong and durable, capable of sustaining great weight and adapted to hold the composition firmly in place and at the same time preventing any springing or yielding movement of the base, while at the same time affording the maximum amount of strength for use.

These objects together with other objects readily apparent to those skilled in the art, I attain by the construction illustrated in the accompanying drawing.

In the accompanying drawing: Figure 1 is a fragmentary perspective view of the metallic base, showing a composition placed upon the base. Fig. 2 is a transverse section. Figs. 3 and 4 are transverse sections of bases showing slight modification.

In the views of the drawing similar reference numerals indicate similar parts.

The base is formed from a sheet of metal, said sheet being so bent or stamped as to form parallel oppositely disposed relatively wide and relatively narrow channel like grooves. The narrow grooves are formed of dove-tailed shape in cross section, the relatively wide grooves alternating with the relatively narrow groove throughout the parallel series the relatively wide grooves thus all opening on one side of the sheet and the relatively narrow grooves all opening on the other or opposite side.

In the drawings I have indicated the metallic sheet by the numeral 1, the narrow dove-tailed grooves by the numeral 2 and the wide dove-tailed grooves by the numeral 3. In the preferred form the bottoms of the dove-tailed grooves are provided with the ridges 4, said ridges located about midway between the walls or boundaries of the dove-tailed grooves, the tops of the relatively wide grooves are arched, the arch being made up of the flat central portions 5 and the beveled or inclined portions 6. All of

said parts being formed integral with the sheet 1. The object and purposes of so forming the tops of the relatively wide grooves is to strengthen the tops of the relatively wide grooves and thereby prevent any sagging or springing of said tops. It is well understood in the construction of the floors made up of sheet metal bases and composition that the base should be free from any springing action, owing to the fact that such springing action of the base has a tendency to crack the composition. It will be understood that when the composition is placed in proper relative position upon the sheet metal base the open dove-tailed grooves 2 will be filled with the composition, thereby preventing any inward movement of the walls of the dove-tailed grooves, owing to the fact that said walls are snugly seated against the composition and by reason of this fact the arched portions of the tops of the relatively wide grooves will not be sprung or bent down as there can be no movement of the walls of the dove-tailed grooves toward each other. It will also be understood that by providing beveled or inlined portion 6 there can be no upward movement or bulging movement of the beveled portions as said beveled portions are located in contact with the composition and consequently the comparatively narrow plain top portions 5 of the relatively wide grooves cannot be sprung or bent down. In Figs. 3 and 4 slight modifications are illustrated as for instance the tops of the open grooves 2 are convexo-concave in their central portions and between the walls of the dove-tailed grooves and said convexo-concave portions, the plain portions 7 are located. The dove-tailed grooves are also formed without the ridges 4, otherwise the construction of the sheet of the base is substantially the same as that shown in Figs. 1 and 2.

In Fig. 4 the tops or open grooves are formed by two inclined sections 8, the apexes of said sections being located about midway between the walls of the dove-tailed grooves and the bottoms of the dove-tailed grooves are formed with V-shaped ridges 9, said ridges extending to the bottoms of the walls of the dove-tailed grooves and their apexes located about midway between the walls of said dove-tailed grooves.

In the modified forms the same general

characteristics as to the tops of the relatively wide grooves are carried out; that is to say the springing or bending down of the tops are prevented in each instance the only difference being the slight changes in the formation or particular shape of the arches. The same being true as to the ridges being formed in the bottom of the dove-tailed grooves, said ridges in both instances being for the purpose of adding rigidity to the sheet proper.

Having fully described my invention what I claim as new and desire to secure by Letters Patent, is—

16. In a base for composition floors formed of sheet metal and provided with relatively

narrow and relatively wide grooves, said relatively wide and relatively narrow grooves opening on opposite sides of the sheets, the tops of the relatively wide sheets 20 arched and the bottoms of the relatively narrow grooves provided with ridges, said ridges located in the openings of the relatively narrow grooves, substantially as and for the purpose specified.

In testimony that I claim the above, I have hereunto subscribed my name in the presence of two witnesses.

JULIUS H. SCHLAFLY.
